(57) **CLAIM**
The ornamental design for a combined electronic device and attachment, as shown and described.

DESCRIPTION

FIG. 1 is a front perspective view of a combined electronic device and attachment showing the new design, shown separately from the attachment for ease of illustration; FIG. 2 is the front view thereof; FIG. 3 is the rear view thereof; FIG. 4 is the side view thereof; FIG. 5 is another side view thereof; FIG. 6 is the top view thereof; FIG. 7 is the bottom view thereof; FIG. 8 is a top perspective view of the attachment shown separately from the electronic device for ease of illustration; FIG. 9 is the front view thereof; FIG. 10 is the rear view thereof; FIG. 11 is the side view thereof; FIG. 12 is another side view thereof; FIG. 13 is a top view thereof; FIG. 14 is the bottom view thereof; FIG. 15 is the bottom perspective view thereof; FIG. 16 is a front perspective view of the combined electronic device and attachment shown with the attachment removed from the electronic device in a first position; FIG. 17 is a perspective view thereof with the attachment in a second position; FIG. 18 is a perspective view thereof with the attachment in a third position; and, FIG. 19 is a perspective view thereof with the attachment in a fourth position.
The broken lines surrounding unshaded regions in the drawings illustrate the bounds of the claim. The broken lines and the unshaded regions bounded by broken lines form no part of the claimed design.
